UNITED STATES PATENT OFFICE.

ESTELLE A. BOYDEN, OF WORCESTER, MASSACHUSETTS.

DESIGN FOR A RADIATOR-CLEANING BRUSH.

SPECIFICATION forming part of Design No. 34,789, dated July 16, 1901.

Application filed April 9, 1900. Serial No. 12,255. Term of patent 7 years.

To all whom it may concern:

Be it known that I, ESTELLE A. BOYDEN, a citizen of the United States, residing at Worcester, in the county of Worcester and State of Massachusetts, have invented a new and useful Design for a Radiator-Cleaning Brush, of which the following is a specification.

The accompanying drawing is a perspective view of a radiator-cleaning brush embodying my design.

My design, as shown in this drawing, is characterized by a handle or body portion A, having a backwardly-curved end, with a small bristled section B extending from the

concave side thereof and a main bristled section C extending from the opposite side of the body portion A.

Having thus fully described and illustrated my design, what I claim, and desire to secure 20 by Letters Patent of the United States, is—

The design for a radiator-cleaning brush, substantially as shown.

In testimony whereof I have hereunto set my hand in the presence of two subscribing 25 witnesses.

ESTELLE A. BOYDEN.
